CLAIM

The ornamental design for a carpentry push block, as shown and described.

DESCRIPTION

FIG. 1 is a right side perspective view of a carpentry push block of my new design.

FIG. 2 is a left side perspective view thereof.

FIG. 3 is a left side view thereof.

FIG. 4 is a right side view thereof.

FIG. 5 is a front view thereof; and,

FIG. 6 is a rear view thereof.

The broken lines in the drawings form no part of the claimed design.
